ABSTRACT OF THE DISCLOSURE

In a coin-operated vending machine, a pushbutton selector assembly, whereby, on depositing a coin, one may, by pushing a particular button, select one of a series of different articles available to be vended. Novel structural and operative features are provided for locking the assembly on such actuation of the button until delivery of the so-selected article, for actuating the selected article vending mechanism and for resetting the buttons after discharge of the article.

This invention relates to a machine for vending of a selected article on depositing a coin, a selector button actuating the vending circuit for the desired articles. Pursuant to the invention means are provided for automatically holding the selector button, when pressed, locked against release, until completion of the vending cycle, and for automatically locking the remaining buttons, precluding actuation of any until the completion of the vending cycle for the selected article, whereupon all buttons are released to normal position, and are thus made available for (the next occasion of selective actuation of a button for repetition of the cycle).

Pursuant to the invention, the button assembly, locking mechanism and switch holding means may be manufactured as a complete unit, which is compact, rugged and durable in use, and which may be readily installed and wired to the vending circuits to be controlled, in a convenient and positive fashion, and readily secured to the vending machine or removed therefrom for inspection, servicing and replacement.

The drawings, illustrating procedure and devices useful in carrying out the invention, and the description below, are exemplary only of the invention, which shall be deemed to cover all other devices and procedures coming within the scope and purview of the appended claims.

In the drawings, wherein similar reference characters indicate like parts:

FIG. 1 is a partly fragmentary, top plan view of a pushbutton selector assembly embodying the invention, with the plungers shown in normal (open) position, taken at the top of FIG. 5.

FIG. 2 is a partly fragmentary bottom plan view thereof taken at line 2—2 of FIG. 5.

FIG. 3 is a fragmentary sectional, elevational view, taken at line 3—3 of FIG. 5.

FIG. 4 is a top plan view thereof, with one button shown pressed.

FIG. 5 is an enlarged transverse sectional view taken at line 5—5 of FIG. 1.

FIG. 6 is a fragmentary bottom plan view, showing the position of the parts on pressing a selector button, and

FIG. 7 is a fragmentary top plan view, showing the position of the parts on so pressing a selector button and movement of the plate, locking the button.

As shown in the drawings, the device comprises a casing 10 of preferably tubular, hollow, elongated form (FIG. 1) with (FIG. 5) top and bottom wall portions 11, 12 and front and rear portions 13 and 14, fabricated of

2

one or more pieces of material to define an essentially hollow casing. The casing 10 may be formed unitarily, or, as shown in FIG. 1, of several pieces of suitable material, secured together in any desired or convenient manner. The front and rear portions 13, 14 thereof are apertured or otherwise formed to slidably receive a series of buttons 15, which may be of any desired number (preferably corresponding with the number of vending circuits for the different products to be vended) and controlled by switches such as 31, 32. The buttons 15 so slidably mounted in the front and rear portions 13, 14 of casing 10 are urged to a first (inoperative) position at which they all are normally urged to partly extend or project (FIGS. 1, 2) out of the casing, by springs 16 positioned (FIG. 5) around the button interiorly of the casing and bearing at opposite ends against the inner face of the rear wall 14 of the casing and against the pin 17 which passes through and is thus carried by the button or plunger 15; a description of one button will suffice for all.

Pins 17 pass (FIGS. 3, 5) through (and are thus keyed to) the plungers 15 and extend therebeyond and through aligned apertures 18, 18' (FIGS. 5, 6, 7) respectively of the top and bottom wall portions 11, 12, of the casing 10, adjacent the front wall 13.

An elongated plunger latching plate 22 (FIGS. 1, 4, 5, 7) is slidably positioned on the upper wall 11 of the casing in any suitable or convenient manner, as for example, by studs 23 fixed to and extending upwardly of the upper wall 11 of the casing and freely passing through slots 24 in the plate 22, to thus axially slidably mount the plate 22. The plate 22 is normally urged to a first position, so that the pins 17 (fixed to buttons 15) will be freely reciprocably received in the apertures 18, 18' of the casing and in the L-shaped slots 25 in plate 22. The slot 25 has (FIGS. 1, 4) a major elongated mouth portion 27 terminating at the forward edge 28 of the plate 22 and aligned with the aperture 18 of top wall 11 of the plate 22 in the (normal) position of the latter responsive to spring 30 or other means (FIG. 1). The spring 30 may (FIG. 1) be secured to opposite ends to plate 22 and to the casing or to the pin 23 extending from the casing.

Pursuant to the invention, means are actuated automatically responsive to movement of a button 15 (customarily marked or aligned with indicia regarding the article of merchandise to be thus vended). The selected button is thus moved, for example, to the position shown at A in FIGS. 4, 7, whereupon means, provided pursuant to the invention, automatically move plate 22 axially (B, in FIG. 3) against the tension of spring 30 until the pin 17 is (FIG. 7) received and locked in the lower end 46 of slot 25; electrical means, thus actuated, may include a switch or switches 31, 32 having actuating pins or arms 32' in the path of movement of pin 17 responsive to movement of a movement of plunger 15. Thereby means 33—such as (FIG. 1) electromagnetic, solenoid, or other suitable means, connected as at 34, with extension 22' of locking plate 22 are actuated. The mouth portion 27 of slot 25 thus moved past the location of the casing aperture 18, locks (FIG. 7) the pin portion 17 of the so pressed (FIG. 3) button 15. Pin 17 so locked, is urged by spring 16 into abutment with flange 35 of plunger locking plate 22. Flanges 35 of plate 22 are spaced apart by the throat portions 27 so formed in the plate.

On movement of a selected button, the plunger casing 22 moving from its normal (FIG. 1) to locking (FIG. 7) position, the pin 17 of the plunger so moved is (due to spring 16) held against the angularly formed leading edge 47 of flange 35 and so held until return of plate 22 to its normal (FIG. 1) position. Means may be provided, pursuant to the invention, for automatically concurrently

locking the remaining plungers on movement of one plunger.

The solenoid or other holding component 33, so energized on movement of a selector button 15, holds plate 22 against accidental retraction until the completion of, for example, a vending cycle or circuit. The switch 32 so closed (for example) by the so moved plunger 15 closes the vending circuit for a predetermined time lapse or until discharge of the article vended or other desired cycle termination. At or prior to such time the solenoid holding circuit is opened and the solenoid de-energized, releasing the plate 22, the latter returning to normal (FIG. 1) position responsive to spring 30.

Pursuant to the invention, means are provided for locking the particular plunger when actuated as above described. Said means may (FIGS. 3, 4) comprise a plurality of discs 38 freely slidably disposed axially in the casing adjacent the front wall 10 thereof beneath (FIG. 5) the top portion 11 of the casing 10 and intermediate said top portion and a channel plate 39 spaced therefrom. Discs 38 are thus movable in a plane angularly of the plane of movement of the buttons 15. The discs are arranged normally in line with the pins 17, a pair of discs abutting in line with a pin and thus being readily separable while so aligned but resisting movement of the pin when not so aligned. Means other than discs, switches and the like may be used in lieu thereof within the scope and purview of this invention. On actuation of plunger 15, its pin 17 is moved therewith (FIG. 2) to a position intermediate a pair of discs 38 (FIG. 3); all of the discs are thus shifted out of line when, due to movement of one pin aligned pair of discs, the remaining (FIG. 4) disc pairs abutment points are offset from or disaligned in relation to the other pins; the latter and their plungers are locked against movement. This condition continues while one plunger remains pressed or locked, thus preventing movement of another plunger during that time.

The flanges 35 are spaced along the forward edge of plate 22 so as to define therebetween openings to the angled major elongated mouth portions 27 of slots 25, the flanges being disposed in crossing relation to the casing apertures 18 in the normal position of plate 22 (FIG. 1). On pressing a button 15, its pin 17 actuates (FIG. 6) the switch associated with the button. The pin would contact the mouth portion 27 of slot 25 to move the plate 22 on such movement of button 15 supplementary to or in lieu of or in aid of movement of plate 22 pursuant to actuation of the switch 32. The leading edges 47 of flanges 35 (that is, the end of the flange first to register with the pin on movement of the plate) is outwardly directed so as to ease the pin into position if the button is not fully pressed or held; the opposite (or trailing) 28 of flange 35 is downwardly inclined.

While the foregoing disclosure of exemplary embodiments is made in accordance with the patent statutes, it is to be understood that the invention is not limited thereto or thereby, the inventive scope being defined in the appended claims.

We claim:

1. In a machine for selectively vending a product on movement of a selective one of a series of plungers axially slidably disposed in a casing in the machine, and normally urged to extend therefrom in a first position, a plate 5 movably disposed on said casing, pins secured to said plungers and extending therefrom and movable therewith, said casing and plate having slots therein for such movement of the selected plunger pin therein, said casing slots being disposed parallel to the axis of movement of said plungers in said casing, flanges on said plate partially disposed adjacent said plate slots, so that portions of the plate slots will be disposed beyond said flanges, means urging the plate to a predetermined first position, wherein the portions of the plate slots beyond the flanges are disposed in crossing relation to the casing slots, so that on movement of the selected plunger, the pin thereof may be moved in said casing slot and into said plate slot portion beyond said flange, and means, actuated on such movement of the said pin of selected plunger into said portion of said plate slot, to move the plate from said first position to a position wherein the said plate flange will be disposed in crossing relation to the casing slot, to thereby prevent the so selected plunger pin from moving out of said portion of said plate slot and thereby holding said so selected plunger in its said so moved position.

2. In a machine for selectively vending a product, as set forth in claim 1, said slots in said plate each having an angled mouth portion beyond said plate flange to facilitate entry of the selected plunger pin into the said portion of the slot, beyond the flange.

3. In a machine for selectively vending a product, as set forth in claim 2, said flanges having leading edges outwardly directed relative to the plate slots, to facilitate movement of said pin of the plunger so moved out of said portion of said plate slot on return of said plate to its said first position.
